(57) **CLAIM**

The ornamental design for a cereal spoon, as shown and described.

DESCRIPTION

FIG. 1 is an elevational view of a cereal spoon showing our new design, and is exemplary of the spoons shown in FIGS. 5-128;

FIG. 2 is a top plan view of the cereal spoon of FIG. 1, and is exemplary of the spoons shown in FIGS. 5-128;

FIG. 3 is a side plan view of the cereal spoon of FIG. 1, and is exemplary of the spoons shown in FIGS. 5-128;

FIG. 4 is a front plan view of the cereal spoon of FIG. 1, and is exemplary of the spoons shown in FIGS. 5-128;

FIG. 5 is a top plan view of a fragmented spoon showing the capital letter “A”;

FIG. 6 is a top plan view of a fragmented spoon showing the capital letter “B”;

FIG. 7 is a top plan view of a fragmented spoon showing the capital letter “C”;

FIG. 8 is a top plan view of a fragmented spoon showing the capital letter “D”;

FIG. 9 is a top plan view of a fragmented spoon showing the capital letter “E”;

FIG. 10 is a top plan view of a fragmented spoon showing the capital letter “F”;

FIG. 11 is a top plan view of a fragmented spoon showing the capital letter “G”;

FIG. 12 is a top plan view of a fragmented spoon showing the capital letter “H”;

FIG. 124 is a top plan view of a fragmented spoon showing the numeral “6”;

FIG. 125 is a top plan view of a fragmented spoon showing the numeral “7”;

FIG. 126 is a top plan view of a fragmented spoon showing the numeral “8”;

FIG. 127 is a top plan view of a fragmented spoon showing the numeral “9”; and,

FIG. 128 is a top plan view of a fragmented spoon showing the numeral “0”.
